UNITED STATES PATENT OFFICE

NAPOLEON KING, OF PAINCOURT, ONTARIO, CANADA

CHURN

Application filed July 16, 1928, Serial No. 293,247, and in Canada June 8, 1928.

This present invention relates to new and useful improvements in a churn and has for its primary object the provision of a churn insert of simple and improved construction and operation which may be readily employed in the outer casing or tank of a conventional type of clothes washer and the operating means of the latter employed for operating the operative parts of the churn 10 insert.

Another object of the invention resides in the provision of a churn of the character stated which is of simple construction and includes a special form of dolly which fits on 15 the central shaft of the washing machine and operates with said shaft.

A further object of the invention resides in the provision of a churn of the character stated which is formed in such a manner that 20 the tank of the churn insert rests on the bottom of the main tank or body and in spaced relation thereto and the depending discharge or drain tube of the churn insert is seated in the drain pipe in the bottom of the main tank 25 or body and normally closed, to prevent the churn insert from rotating with the shaft, thus holding firmly in position the body or tank of the insert while the dolly operates therein.

30 A still further object of the invention resides in the provision of a churn insert of the character stated which may be readily placed in position within the main tank or body of the conventional clothes washer after removal of the regular dolly for the clothes 35 washing machine, and the dolly of the churn insert substituted on the drive shaft of the machine, said shaft extending upwardly through airtight bushings in the bottom of the churn insert body or tank and through the dolly of the churn insert with the latter firmly mounted on said shaft for operation within the body or tank of the churn insert.

40 A still further object of the invention resides in the provision of a churn insert of the character stated having special means for normally closing the drain tube depending from the body or tank of the churn insert 45 and for operating the closure valve of the

drain tube when it is desired to drain the churn insert body or tank.

A still further object of the invention resides in the provision of a churn insert of the character stated which is of such construction and operation as to assure successful churning of the contents thereof and production of a high grade butter within the minimum period of time by employment of the operating mechanism which also serves to 55 operate the operative mechanism of the machine when employed as a clothes washer.

To the accomplishment of these and related objects as shall become apparent as the description proceeds, my invention resides in the construction, combination and arrangement of parts as shall be hereinafter more fully described, illustrated in the accompanying drawings and pointed out in the claim 60 hereunto appended.

The invention will be best understood and can be more clearly described when reference is had to the drawings forming a part of this invention wherein like characters indicate like parts throughout the several views.

In the drawings:—

Figure 1 is a vertical transverse section through a washing machine of conventional form with the dolly thereof removed and my improved churn insert mounted in position; 70 within the main tank or body of the machine, the lower portion of the latter being in elevation;

Figure 2 is a perspective of the churn insert, removed;

Figure 3 is a bottom plan of the churn insert;

Figure 4 is an elevation of the churn insert dolly;

Figure 5 is a top plan of the churn insert 80 dolly; and

Figure 6 is a bottom plan of the churn insert dolly.

Referring more in detail to the drawings, it is to be noted that the churn insert includes 95 a tank or body 11 of considerably smaller diameter than the tank or body 12 of the washing machine 13, the upstanding central operating shaft 14 of which works through watertight bearings 15 in the center of the 100

bottom of the tank or body 12 and which bottom is designated by the numeral 16 and has the edge 17 thereof curved upwardly as it connects with the upstanding side wall of the tank or body 12. The entire washing machine is of conventional form, such as the one known on the market at the present time as the Coffield washer.

The churn insert tank or body 11 is also more shallow than the washing machine or body 12 and has a removable cover 18 with a depending annular flange 19 near its edge for engagement in the top of the tank or body 11 and thus form a watertight connection between the tank or body 11 and the cover 18. A depending annular supporting flange 20 is also provided on the bottom of the tank or body 11 to support the same in the washing machine tank or body 12 and centrally thereof as well as in spaced relation to the bottom 16 of the washing machine tank or body 12, with the operating shaft 14 extending upwardly through the watertight bearing 21 in the center of the bottom 22 of the churn insert tank or body 11.

When converting the washing machine into a churn, the cover 22 for the washing machine tank or body 12 is removed and the washing machine dolly is taken off of the operating shaft 14. The tank or body 11 of the churn insert is then placed in position on the upper end of the shaft 14, within the washing machine body or tank 12 and the churn dolly 23 secured on the upper end of the operating shaft 14 within the tank or body 11 for operation with the shaft 14. This churn dolly 23 includes a lower cross 24 and a smaller upper cross 25 with the pairs of corresponding arms 26 and 27 of the crosses 24 and 25 respectively, arranged in parallel relation to support therebetween the upstanding agitating panels 28 which extend radially from and are spaced outwardly of the operating shaft 14. Each panel 28 has an enlarged and rounded outer lower corner 29, whereby the width of the panel 28 is increased at this portion and thus strengthened to assure more efficient operation of the churn. It may also be stated at this time that the panels 28 have reduced extensions at their upper and lower edges secured in appropriate recesses 30 provided therefor in the arms 26 and 27 of the lower and upper crosses 24 and 25, respectively. Depending from the bottom 22 of the churn insert tank or body 11 is the drain tube 31, at one side of the center of said bottom 22 and when the churn insert is in position within the washing machine body or tank 12, the drain tube 31 depends in the drain pipe 32 of the washing machine tank or body 12, thus preventing rotation of the churn insert tank or body 11 within the outer tank or body 12. A closure slide valve plate 33 operates transversely in the drain pipe 31 and has a valve opening 34 which is adapted

to register with the opening of the drain pipe 31 when it is desired to drain the tank or body 11. During the churning operation, however, the slide valve plate 33 should be in closed position, as illustrated. A control rod 35 is attached to the plate 33 and to one corner of the triangular plate or bell crank member 36 which is pivotally mounted on the supporting bracket 37 provided therefor on the outer face of the tank or body 11 and adjacent the bottom thereof. To another corner of the triangular plate or bell crank member 36 is the upstanding operating rod 38 therefor working through an appropriate guide 39 projecting from the side of the tank or body 11. The upper end of the operating rod 38 terminates in a ball or head 40, by means of which the rod 38 may be readily held and operated.

As the construction of the device has thus been described in detail, brief reference is now had to its use and modus operandi: For converting the washing machine into a power churn, the washing machine cover 22 is removed and the washing machine dolly taken off of the operating shaft 14. The churn insert tank or body 11 is then mounted on the shaft 14 and within the washing machine tank or body 12, with the drain pipe 31 of the tank or body 11 depending into the washing machine tank or body drain pipe 32, after removal of the stopper or cork from the latter. The churn dolly 23 is then firmly mounted on the upper end of the operating shaft 14, within the tank or body 11. The operating rod 38 should be in such position as to insure closing of the valve plate 33. Then, after the milk to be churned into butter has been supplied to the tank or body 11, the shaft 14 may be operated in the usual manner to operate the churn dolly 23, without any further changes or alterations in the construction or operation of the washing machine. Furthermore, as the milk only comes in contact with the interior of the tank or body 11 and the dolly 23 of the churn insert and the upper end of the operating shaft 14, there is no possibility of the milk or the butter churned therefrom coming in contact with the parts of the washing machine which may be affected by employment of the machine for washing clothes. The operating shaft 14 with its smooth surface at its upper squared end, may always be kept clean and sanitary and if desired a sleeve may be provided for completely covering and enclosing this portion of the operating shaft 14 when employing the machine for churning operations or for washing operations. The draining of the tank of body 11 may be accomplished while the churn is in position within the outer tank or body 12 or when removed therefrom, as desired.

From the foregoing description, taken in connection with the accompanying drawings,

it will be manifest that a churn is provided that will fulfill all the necessary requirements of such a device but as many changes could be made in the above description and many 5 apparently widely different embodiments of my invention may be constructed within the scope of the appended claim without departing from the spirit or scope thereof, it is intended that all matters contained in the said 10 accompanying specification and drawings, shall be interpreted as illustrative and not in a limited sense.

Having thus described my invention, what I claim as new and desire to secure by Letters Patent is:—

15 A churn insert including the combination with the operating shaft of a washing machine and a churn dolly accommodating insert tank removably mounted thereon; of a 20 churn dolly comprising a large lower cross and a small upper cross; pairs of radiating upstanding dolly panels having spaced vertical inner edges and curved outer edges increasing the width of the lower portions of 25 said panels; said panels having reduced lower and upper extensions engaged respectively in slots in the radial arms of said large lower cross and said small upper cross; and means for securing said extensions in their respective slots; said dolly being adapted for removable mounting on the upper end of the 30 said operating shaft of the washing machine within the said churn dolly accommodating insert tank and adapted for rotation with 35 said shaft.

In testimony whereof I hereunto affix my signature.

NAPOLEON KING. [L.s.]
